[57] CLAIM

The ornamental design for a boat motor mount, as shown and described.

DESCRIPTION

FIG. 1 is a perspective view of the boat motor mount showing my new design.

FIG. 2 is a front elevation view, taken along line 2—2 of FIG. 1.

FIG. 3 is a right-side elevation view, taken along line 3—3 of FIG. 2.

FIG. 4 is a top plan view, taken along line 4—4 of FIG. 2.

FIG. 5 is a left-side elevation view, taken along line 5—5 of FIG. 2.

FIG. 6 is a bottom plan view, taken along line 6—6 of FIG. 2.

FIG. 7 is a rear elevation view, taken along line 7—7 of FIG. 1.

FIG. 8 is a perspective view of a second embodiment of the boat motor mount.

FIG. 9 is a front elevation view of the second embodiment shown in FIG. 8, and taken along line 9—9 of FIG. 8.

FIG. 10 is a left-side elevation view, taken along line 10—10 of the second embodiment shown in FIG. 9.

FIG. 11 is a top plan view of the second embodiment, taken along line 11—11 of FIG. 9.

FIG. 12 is a right-side elevation view of the second embodiment, taken along line 12—12 of FIG. 9.

FIG. 13 is a bottom plan view of the second embodiment, taken along line 13—13 of FIG. 9.

FIG. 14 is a rear elevation view of the second embodiment, taken along line 14—14 of FIG. 8.
